(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a left side elevational view thereof, the right side elevational view is a mirror image of the left side view;

FIG. 5 is a top plan view thereof;

FIG. 6 is a bottom plan view thereof; and,

FIG. 7 is a front perspective view similar to FIG. 1 in the open position with a guide extended from the chute.

The broken line in the drawings is for illustrative purpose only and forms no part of the claimed design.

1 Claim, 3 Drawing Sheets
